UNITED STATES PATENT OFFICE

JAMES H. BUCHANAN, OF LOS ANGELES, CALIFORNIA

PHONOGRAPH SOUND REPRODUCER

Application filed June 19, 1929. Serial No. 372,010.

My invention is a phonograph sound reproducer, which by the medium of light and electrical vibrations transforms the vibrations of the stylus into sound.

5 A main object of my invention is reproducing sound from a phonograph record, by utilizing the vibrations of the stylus to control a fluctuating light and utilizing such light in connection with a photoelectric cell 10 or the like to reproduce sound.

Another object of my invention is an apparatus and method of reproducing sound from a phonograph record, by causing the vibrations of the stylus to cause a vibratory 15 interruption of the beam of light and to use such beam of light in the reproduction of sound.

A more particular object of my invention is utilizing a phonograph stylus which is 20 vibrated by a record, causing such stylus to vibrate a light interrupter which is positioned between a source of light and a photoelectric cell and then utilizing the current controlled by the cell to reproduce sound.

25 Another object of my invention is in mounting the apparatus having the stylus, the light interrupter, the source of light and the photoelectric cell, on a carriage which is movable over a phonographic record, whereby 30 the vibrations of the stylus causes a vibration of the light interrupter and thence the photoelectric cell controls the development of the sound.

In this connection a more detailed object 35 of my invention is moving the carriage and stylus by a screw operated from the turntable spindle of a disk type of record rotator, so that the carriage follows the grooves on the record and thus produces the recording complete from the periphery to the center portion of the disk.

In constructing my invention I preferably have a pair of tracks located on opposite sides of the turntable for using a disk type of record and slidably mounted on these tracks. I have a bridging frame which has the carriage thereon. The carriage contains the light interrupter which is in the form of a light vibrating reed which vibrates across a 50 narrow slot under the action of the stylus,

and is adapted to engage the grooves of the record. The carriage also mounts a lamp, a suitable lens system and a photoelectric cell with a small amplifier positioned adjacent the cell.

The screw for shifting the carriage has a mounting on one side of the turntable allowing a universal movement of one end of the screw. The other end of the screw has a gearing which may be connected to the 55 spindle of the turntable and thus rotate the screw to give the carriage a transverse movement from the periphery towards the center of the disk, whereby the stylus may correctly pick up the vibrations cut into the record. 60 The current from the photoelectric cell after amplifying is reproduced by a loud speaker or the like.

My invention is illustrated in the accompanying drawings, in which,

70 Figure 1 is a plan of the vibration transforming device mounted above a phonographic turntable;

Fig. 2 is a vertical section taken on the line 2—2 of Fig. 1, in the direction of the 75 arrows;

Fig. 3 is a vertical section on the line 3—3 of Fig. 1, in the direction of the arrows;

Fig. 4 is a horizontal section substantially 80 on the line 4—4 of Fig. 3 in the direction of the arrows;

Fig. 5 is an electrical diagram of a connection from a photoelectric cell to an amplifier, suitable for connection to a loud speaker.

85 In the drawings a phonograph cabinet is indicated by the numeral 11 having a top 12 and on this top there is mounted the usual rotatable turntable 13. This turntable is mounted on a rotatable spindle 14. The 90 table has the usual felt covering 15 or the like. The phonograph disk is indicated by the numeral 16. This is shown as the type having the zigzag or lateral recording thereon.

95 An instrument box 17 is mounted on a carriage 18, this carriage having side bars 19 with curled bearing ends 20 and which ends slide on tracks 21 which are illustrated as being round bars and such bars are supported 100

on pedestals 22 extending upwardly from the top of the phonograph cabinet or table. The instrument box is illustrated as being slightly spaced from the carriage structure, which structure in reality may be merely a continuation of the side bars 19. The bottom of the bars have studs 23 extending downwardly and the spring 24 between the heads of the studs and the bottom of the bars 19.

10 The shifting of the box across the vertical record is accomplished by means of a lead screw 25 which at one end has a ball 26 mounted in the spherical bearing 27, this bearing having a removable cap 28 and being mounted on a pedestal 29 extending upwardly from the top of the vertical cabinet. The other end of the screw has an arcuate frame 30 connected thereto, this frame forming a journal 31 for the inner end of the screw 25 and also forming a journal having a vertical stub shaft 32. This stub shaft has a socket member 33 thereon adapted to fit over the top of the spindle 14, which spindle is illustrated as having a slot 34 so that the pin 35 attached to the socket extends downwardly into the slot. Therefore the rotating movement of the spindle 14 rotates the socket 33 and hence the stub shaft 32. A bevel gear 36 on the stub shaft meshes with a bevel gear 37 on the screw 25, there being a collar 38 preferably secured to the screw and holding the gears in proper meshing relation. By this construction the screw 25 with the carriage and instrument box may be lifted up, pivoting on the ball 26 mounted in the spherical bearing. This allows changing records and when the screw is again lowered so that the socket 33 interfits with the spindle 14 the rotation of the spindle and hence the turntable and record causes a rotation of the screw 25. There is a half nut 39 secured to the carriage or to the box structure and meshing with the upper portion of the threads on the screw 25, so that when the screw rotates the instrument box is shifted in a radial direction in reference to the record.

15 The box has a depending structure with a chamber 40 in which there is mounted a pivot 41 for a vibrating needle or reed 42. This needle or reed extends downwardly through a slot 43 on the bottom of the depending structure and has a socket structure 44 in which may be engaged a stylus 45 held in place in any suitable manner. The stylus is preferably removable. A partition 46 has a vertical slot 47 therein so that the needle or reed 42 may vibrate across the front of this slot.

20 A source of light is indicated by the lamp 48 mounted in one end of the instrument box and having its light reflected by a reflector 49 passing through an optical system of lenses 50 and then through the slot 47 and being concentrated on a photoelectric cell 51. The light enters the window 52 of the cell. The

cell is wired to a small amplifier 53 adjacent thereto, also preferably mounted in the box and to simplify the illustration, electric leads 54 are indicated as leading to an electro-magnetic sound producing unit 55 which has a horn or the like 56 connected thereto.

25 In Fig. 5 I illustrate one type of electric connection to the photoelectric cell. An energizing source of power is indicated by the battery 57, there being circuit leads 58 and 59 from the battery through a resistance 60 to the terminals of the photoelectric cell. The current flows to a tube amplifier 60' having a connection 61 to the grid of the tube. The tube is energized by a battery 62, there being a resistance 63 in the battery circuit.

30 My invention as above mentioned, is adapted to be used particularly with records having a lateral or zigzag sound recording thereon. My invention may be utilized for disks in which the sound record starts at the outside and works towards the inside and in which the record starts on the inside and works outwardly towards the outside. After the disk is positioned the screw is connected to the spindle to be driven thereby and the instrument box with its carriage is mounted on its rails or the equivalent so that when the screw rotates and engages the half nut 39, the instrument box is shifted. The screw is arranged to synchronize with the grooves in the record which are cut in a spiral manner on the disk.

35 As the disk rotates the stylus 45 is vibrated and this causes a rocking vibration of the reed 42, this operating across the slot or aperture 47, whereby the light from the lamp 48 is interrupted in passing through the said slot. The light rays are picked up by the photoelectric cell which has its electrical functions varied and transmits a varying electric current preferably through an amplifier to a loud speaking horn. Hence the mechanical vibrations set up by the phonograph record are through the action of changes of light caused to form an electrical fluctuating current having characteristics similar to the wave form of the sound wave on the record. Therefore the electric current may be utilized to operate a loud speaker.

40 By my equipment it will be seen that I may reproduce sounds by changing the mechanical vibration of the stylus into the vibration of a light intercepting device which causes a vibration in a beam of light and this beam of light affecting the photoelectric cell causes a transposition into an electrical vibration, which electrical vibration is transformed into sound. Thus my invention comprises not only the apparatus but the method of reproducing sound from a mechanical vibration derived from a phonographic record to a vibration of light and then by electrical vibrations and thence the sound.

45 Various changes may be made in the prin-

ciples of my invention without departing from the spirit thereof as set forth in the description, drawings and claims.

I claim:

5. 1. A sound reproducer comprising in combination a turntable adapted to support a phonograph record and having a rotatable spindle, a pivotally mounted screw, a stub shaft adapted to engage the spindle, a driving 10 connection between the stub shaft and the screw, a vibratory device having a mounting shiftable by the screw, means to direct a beam of light on an electric light responsive device, the vibratory device being positioned to 15 intercept the beam and cause a variation of the illumination of the light responsive device.

2. A sound reproducer as claimed in claim 1, the screw and the stub shaft having an interconnection whereby the bodily shifting of 20 the screw may engage or disengage the stub shaft from the said spindle.

3. A sound reproducer comprising in combination a rotary turntable for a phonograph 25 record, a rotary spindle, a screw pivotally mounted at one end to have a pivoting and a rotary motion, a stub shaft connected to the screw and adapted to engage the spindle to be driven thereby, a driving connection between 30 the stub shaft and the screw, a supporting track, a carriage mounted thereon and having an engagement with the screw, a source of light in the carriage, adapted to project a beam of light, an electric light responsive device to receive the beam, a mechanical vibratory device having a part thereof to engage 35 the record and another part to intercept the beam of light.

4. A sound reproducer comprising in combination a rotatable spindle having a rotatable disk to support a phonograph record, a socket structure fitting thereon and having a vertical stub shaft journaled therein, a horizontal lead screw having a pivotal mounting 45 beyond the periphery of the disk, a drive connection from the stub shaft to the said screw, an instrument box having a connection to said screw and with a vibratory stylus to engage a record, a reed connected to the 50 stylus, a source of light with means to transmit a beam of light past the said reed, and means to receive and reproduce electrical signals from the transmitted light.

5. A sound reproducer comprising in combination a cabinet top having a rotatable spindle with a turn table thereon for a disk, a pedestal secured to the cabinet top and having a lead screw swivelly connected thereto, a frame connected to the end of the lead screw 60 and having a socket with a stub shaft therein, a geared connection from the screw to the stub shaft and means to connect the stub shaft to the spindle, a pair of guide tracks, an enclosed carriage mounted thereon, a structure 65

having a vertical slot and having a stylus to engage a record, a source of light, a lens to form a beam of light, a photoelectric cell, and an amplifier mounted in the cabinet, the carriage having a support on the said tracks and having a driving connection with the said screw.

6. A sound reproducer comprising in combination a cabinet top having a rotatable spindle with a disk for a record, a pedestal on the cabinet, a lead screw swivelly connected to the pedestal and having a frame at its opposite end, with a stub shaft journaled in said frame, means to connect the stub shaft to the spindle, a geared connection between the stub shaft and the screw, a pair of guide tracks parallel to the screw, an enclosed carriage mounted on said tracks and having a driving connection with said screw, a vibratable device in the carriage operated by a stylus from a record, a source of light forming a beam, a light electric sensitive device, said vibrating device varying the beam of light in accordance with the vibration of the stylus.

In testimony whereof I have signed my name to this specification.

JAMES H. BUCHANAN.
